Ohio, a partnership

Application December 6, 1945, Serial No. 633,111

3 Claims. (Cl. 161—4)

1

The invention disclosed and described in this application relates to a timing device. It may be useful for the timing of industrial operations of various kinds. It may also be useful in industrial and domestic cooking operations. It may also be useful in many other situations which will be recognized by readers of the description following. The invention relates especially to timing devices of the character by which it is possible to time several operations simultaneously.

Heretofore, it has been fairly common to provide a timing device which may be set to give a signal at the end of a predetermined time; but it is not usual to provide such a device which may be set to give signals at the end of two or more predetermined different lengths of time, starting such timing intervals either simultaneously or at different times.

It is therefore an object of my invention to provide a timing device designed to be set simultaneously to time a plurality of different intervals of time.

A further object of my invention is the provision of a timing device which at any time during the timing of one interval may be set to give a signal showing the passage, a subsequent interval of the same or any other predetermined length.

One feature of my invention is the provision of rotatable disk having a plurality of holes formed therein with which may be associated a plurality of removable pins, each pin being adapted to operate switch means so as to give a signal at the end of a predetermined time from the instant at which the pin is inserted in the appropriate opening.

Further objects and features of my invention will be apparent from a consideration of the following specification and claims in connection with the accompanying drawings in which one embodiment of my invention is disclosed for the purpose of illustration.

In the drawings:

Fig. 1 is a view in elevation of a timing device constructed in accordance with my invention;

Fig. 2 is a view in horizontal section taken substantially on the line 2—2 of Fig. 1 looking upward;

Fig. 3 is a view in elevation of the timing device shown in Fig. 1 looking in the opposite direction from that in which the view of Fig. 1 appears; but having the casing removed so that the rear of the front plate and its associated mechanism is seen;

Fig. 4 is a fragmentary view in elevation and on an enlarged scale of a small portion of the

showing of Fig. 1, looking in the same direction and having a portion of the front casing broken away in order to show the signal trip mechanism;

Fig. 5 is a fragmentary view partly in elevation partly in section and on a greatly enlarged scale from that of Fig. 1, being taken substantially on line 5—5 of Fig. 3 and looking in the direction of the arrows but having the rotatable disk, dial, front plate and the angle iron as well as the rear casing omitted;

Fig. 6 is a fragmentary view in section on a still larger scale, having parts broken away and taken substantially on the line 6—6 of Fig. 1 looking in the direction of the arrows;

Fig. 7 is a fragmentary view partly in elevation and partly in section on a scale corresponding to that of Fig. 6, the section being taken substantially on the line 7—7 of Fig. 6, the cover plate and rotatable disk being omitted and a portion of one of the supporting plates being broken away for clarity; and

Fig. 8 is a diagrammatic view showing the electrical circuits used in this embodiment of my invention.

25 In the illustration of my invention disclosed in the drawings hereof, referring especially to Figures 1 and 2, it may be seen that I have shown a casing 11 having a cover plate 12 and a rear casing closure 13. As seen in Fig. 2, the casing is thus sealed and provides a moisture proof container for the mechanism which in one preferred form is about 5½ inches deep. Also, as seen in Fig. 1, the casing is substantially square being approximately 25 inches on each side. The

30 cover plate 12 has formed therewith or secured thereto a circular raised annulus or dial 14 which remains stationary relative to the plate 12 and cooperates with a rotatable disk 15 mounted and driven as will be hereinafter described. The disk 15 is formed with a plurality of holes such as the holes 16. As shown in the illustration of my invention there are 120 of these holes spaced at equal distances around the disk, each of these holes being spaced a distance from the adjacent

35 hole such that the time required in the timer illustrated for one hole to be moved to the position occupied by the adjacent hole by the driving means provided, will be exactly one minute. Thus the disk may be rotated completely in exactly

40 one hundred and twenty minutes or two hours. Each of the holes is adapted to receive a removable pin and as shown, there are three pins 17, 18 and 19 positioned in three of the holes. As will be subsequently explained, each of these pins 45 when it reaches a predetermined position relative

to the annular dial 14 is arranged to close the switch and give a visible and/or audible signal.

I provide means for mounting the disk 15 for revolution upon the casing 11. Referring especially to Figures 2 and 3, it may be seen that the disk 15 is secured to and supported by a rotatable shaft 21. For example, the disk 15 rests upon a shoulder 22 formed on the shaft 21 and is clamped against the shoulder by a brass washer 23 which is held in place by a brass acorn nut 24. The nut 24, as shown, is internally threaded and screws upon the threaded upper end of the shaft 21, pressing against the washer 23, and thus holding the disk 15 in place. The shaft 21 is mounted in bearings 25 and 26 which are formed integrally with or secured to plates 27 and 28, respectively. The plates 27 and 28 are secured to each other and to the cover plate 12 by four supports, two of which are shown in Fig. 2 and designated generally as 29 and 31. Each of the four supports (e. g. 29 and 31) comprises a pair of sleeves or spacers such as 32 and 33 through which there extends a post internally threaded at each end. Each post is secured at its upper end to the upper cover 12 by a screw 34 and at its lower end to the plate 28 by a screw 35. The posts are not shown, but it should be understood that the sleeves 32 and 33 surround their associated post and that the sleeves 32 bear at their upper ends on the plate 27 and at their lower ends on the plate 28, that the sleeves 33 bear at their lower end on the plate 27 and at their upper end on the cover 12 and the screws 34 and 35 clamp the cover 12, plates 27 and 28, the eight sleeves 32 and 33, and the four posts (not shown) tightly together to secure the plates 27 and 28 firmly to the cover 12 and support the assembly. With the above explanation, the construction will be readily understood. Angle irons 37 and 38 (see Fig. 3) are welded to the cover 12; are provided with cutout portions receiving the upper sleeves 33; and aid in supporting the structure under the cover 12, and in bracing the cover.

I provide means for driving the disk 15 at a constant rate of speed. In the embodiment illustrated, as stated above, this speed is such that the disk makes one complete revolution in each one hundred and twenty minutes or two hours. Referring especially to Figures 3 and 5, it may be seen that there is mounted on the plate 27 a synchronous electric motor 41 having a shaft 42, extending through the plate 27 and carrying a small gear 43 which meshes with a larger gear 44 mounted on a shaft 45 extending through both of the plates 27 and 28. The shaft 45 carries a small gear 46 which meshes with the large gear 47. The gear 47 as shown especially in Figures 2 and 3 is mounted on the shaft 21 and is secured to said shaft so that operation of the electric motor 41 (through the gears 43, 44, 46 and 47) drives the shaft 21 and with it drives the disk 15 at a constant speed. Inasmuch as the motor is a synchronous electric motor, the speed of the disk 15 is uniform. The speed of the electric motor is such and the relative gearing of the gears 43, 44, 46 and 47 is such that the disk 15 revolves once in exactly one hundred and twenty minutes or two hours.

I provide means whereby rotation of the disk 15 operates one or more signals to indicate that a certain predetermined time has elapsed. Pins such as the pins 17, 18 and 19 are utilized for this purpose. Referring especially to Figures 1, 4 and 6, it will be noted that the pin 17 extends through the disk 15 and is arranged at times to

contact with the outwardly extending end 48 of a shaft 49. The shaft 49 extends through the cover plate 12 and through a pair of plates 51 and 52 secured (by means which will now be described) to the plate 12. The plate 51 is secured directly to the plate 12 as by welding at 53 and 54 and the plate 52 is secured to the plate 51 by means of screws 56 and 57, and cylindrical spacers 58 and 59 surrounding the screws 56 and 57 and 10 interposed between the plates 51 and 52. The shaft 49 is provided with enlarged portions 61 and 62. The enlarged portion 62 has extending therefrom a trip lever leaf 63 formed at its outer end with a hook 64 (see Fig. 7). The portion 15 62 also has extending therefrom a projection 65 for purposes later described. Similarly mounted between the plates 51 and 52 is a corresponding shaft 66 which is formed with enlarged portions 68, 69 and 70. The enlarger portion 69 is formed 20 with a notch 71 which cooperates with the hook 64 of the trip lever leaf 63 as will subsequently be described. The enlarged portion 70 has secured thereto a radial arm 72 formed with a hooked end 73. At its rear end the enlarged portion 70 also has secured thereto a mercury switch 74 connected in an electrical circuit as will later be described. Parallel to the shafts 49 and 66 is a third shaft 75 which is mounted for rotation in the dial 14. At its forward end it 25 30 carried a knurled head 76 and at its rearward end has an enlarged portion 77. Secured to this enlarged portion is an arm 78. Pivoted connected to the arm 78 and the hooked end 73 is a link 79 which connects the arm 78 and the end 73.

35 Above I have described in general the essential portions of my automatic switch unit including the mountings thereof on the plates 51 and 52 and the various shafts associated therewith. I will now describe the means for urging the shafts 49, 40 66 and 75 resiliently in a counter clockwise direction so that when released the shaft 66 will be turned to close the switch 74 and so that normally the shaft 49 is turned to move the hook 64 into the notch 71 to restrain the shafts 66 and 45 75 against counter clockwise rotation. Thus in the normal position the switch 74 is maintained open.

The projection 65 of the enlarged portion 62 of the shaft 49 has connected to it, a tension spring 50 80 which at its opposite end, is secured to a bracket 81 in turn secured by the screw 56 to the plate 52. A similar bracket 82 is secured to the plate 52 by the screw 57. The bracket 82 is connected to a similar spring 83 which has its opposite end connected to an extension 84 formed on the enlarged portion 69 of the shaft 66. Thus looking at Fig. 7, it may be seen that the springs 80 and 83 tend to urge the shafts 49 and 66, respectively, in a counter clockwise direction as 55 60 shown in Fig. 7. However, when the hook 64 of the trip lever leaf 63 is engaged in the notch 71, the spring 83 is prevented from rotating the shaft 66. In such condition of the parts, the mercury switch 74 is open. Moreover, the contact of 65 70 the hook 72 with the enlarged portion 69, serves as a stop to prevent undesired rotation of the shaft 49 by the spring 80. However, when any pin, as for example the pin 17, contacts the extension 48 of the shaft 49 as shown in Fig. 4, the pin moves the extension 48 and rotates the shaft 49 in a clockwise direction against the action of the spring 80. This removes the hook 64 from the notch 71 and allows the spring 83 to rotate the shaft 66 in a counter clockwise direction. 75 Rotation of the shaft 66 in a counter clockwise

direction tilts the mercury switch 74 so as to close the switch and the associated electric circuit and thus operates one or more signals. When the operator's attention is called to the signal, he knows that the predetermined time has elapsed and attends to the duties required of him by such lapse of time. As soon as he has done so, he may stop the signal or signals by rotating the knurled head 76 and the shaft 75 thus rotating the shaft 66 through the link 79. He thus opens the contacts in the mercury switch 74, breaking the electric circuit, and stopping the signal. This action also resets the mechanism inasmuch as rotation of the shaft 66 allows the spring 80 (assuming that the pin (e. g. the pin 17) has passed the extension 48), to return the hook 64 to the notch 71. The apparatus is ready for the next signal which may be caused by contact of the pin 18 with the extension 48. It is to be understood that the operator may, if he desires, postpone resetting the mechanism for any reasonable length of time provided he has other duties which require his attention, inasmuch as the motor 41 continues to drive the disk 15 regardless of whether the switch 74 is in an open or closed position and regardless of the position of the shafts 49, 66 and 75.

The electric circuit is shown diagrammatically in Fig. 8. Electric current is supplied from a source indicated by the posts 85 and 86. It flows through leads 87a, 87b, 87c, and 87d provided the manual switch 88 is closed, and thus continuously operates the synchronous motor 41. When the mercury switch 74 is also closed, current also flows through leads 89a, 89b, 89c, 89d and 89e and operates the light signal 91 and the bell 92. The light signal 91 is also shown in Fig. 1 but the bell signal 92 and the manual switch 88 are shown only in Fig. 8 inasmuch as I prefer that these parts be provided separately from the unit 11.

In this connection it is clear that my timer can be used for other purposes than that of operating a signal inasmuch as the taps 85 and 86 may be connected to any type of device which it is desirable to operate at the end of a predetermined time or to operate several times at the end of various predetermined times.

Referring again to Fig. 1, it may be seen that I have illustrated arcuate strips 93 and 94 formed with holes 95 into which spare pegs 96 of the type shown in 17, 18 and 19 may be kept when not in use. I have also shown at 97 a clip pointer which may be attached to the annular dial 14 to indicate the point on the dial from which a pin started in the timing operation. Only one of the pointers 97 is illustrated, but the operator could, if he had desired, place one pointer for each of the pins 17, 18 and 19 to indicate the point from which it started. The placing of only the one pointer 97 might be considered to indicate that each of the pins 17, 18 and 19 started from the same place, i. e. the point indicated by the pointer 97. For instance, this might indicate that there were three sets of material being processed, each of the materials requiring a time of eighty and one-quarter minutes, and the position of the pins would indicate that the whole time had elapsed for one set, approximately forty minutes for the second set and approximately twenty minutes for the third set.

It is believed that the operation of my improved apparatus will be apparent from the above description. With parts in the position shown in the drawings we will assume that it was desired to time a series of operations each for a period

of eighty and one-quarter minutes. The operator has inserted the peg 17 in an opening at a time that the opening was at the point indicated by the pointer 97. The synchronous motor 41 continued through the gears 43, 44, 46 and 47 to drive the disk 15 in a clockwise direction. Subsequently it was desired to time additional batches and the pins 18 and 19 were inserted in holes which at the times of their insertion were opposite the pointer 97. When the pin 17 reaches the point shown in Fig. 1, it contacts, as shown in Fig. 4, with the arm 48 and rotates the shaft 49 thus turning the trip lever leaf 63 and removing the hook 64 from the notch 71. This allows the spring 83 to rotate the shaft 66 in a counterclockwise direction closing the switch 74 and through the electric circuit illustrated in Fig. 8, operating the signals 91 and 92. The operator removes the indicated batch of material from the processing operation. After the pin 17 has passed the lever 48, the operator rotates the knurled head 76 in a clockwise direction turning the shafts 75 and 66 clockwise against the action of the spring 83. This permits the spring 80 to rotate the shaft 49 in a counterclockwise direction and move the hook 64 into the notch 71. When the pin 18 reaches the arm 48, it similarly closes the switch and actuates the signals and so also when the pin 19 reaches the arm 48. It may be thus seen that a large number of operations may be timed at the same time by the use of my apparatus; that each timing operation is entirely independent of each other; and that each may start at any time. Little chance is left for the operator to make mistakes inasmuch as all that he had to do is insert the peg which is associated with the indicated batch of material at the time that the process starts. It should be understood that the pegs may be numbered if desired. Numerals such as those indicated at 98 may be placed at appropriate positions on the annular dial 14, it being understood that more or less numerals than are shown may be provided. A clock 99 is also provided. It is also to be understood that though we have at times referred herein to a cooking operation, this apparatus is intended for use not only for timing such operations but also for timing a great variety of industrial processes such as pickling, plating, annealing, polymerization, etc.

From the above disclosure it is apparent that there is provided a process timer which is relatively small, light weight and ruggedly constructed, and which is adapted to be enclosed in a moisture sealed casing. This timing device is self calculating having a timing ring marked at five minute intervals for a two-hour period, which is standard. There is also provided numbered batch or lot pins adapted to be inserted in a rotating disc opposite time units marked on a stationary timing ring. The disc then carries the pin or pins so inserted around to a signal circuit switch which is tripped to close a circuit operating the signal horn. After the switch is closed the pin or pins can be withdrawn and the switch manually returned to the open position. However, it is to be noted that the signal circuit remains closed and the horn continues to blow until the switch is returned to the "off" or open position, thus opening the circuit. In view of the fact that the signal circuit used can be connected to a commercial power source supplying, for example, 110 volt 60 cycle alternating current the timer can be placed almost anywhere within a plant and connected to an industrial type of

howler horn. Such a signal can be heard readily above the usual operating noises, since voltage drop is eliminated and sufficient power can be supplied to operate a loud signal. The timer is also provided with a pilot light which glows when the timer is in operation and with a clock to aid in the timing operation, all of which can be operated from the signal circuit if desired.

It is to be understood that the above described embodiments of my invention are for the purpose of illustration only and various changes may be made therein without departing from the spirit and scope of my invention.

I claim:

1. A timer adapted to signal the passing of predetermined and varying periods of time comprising in combination an electrical signal circuit adapted to be energized from a commercial power source, said signal circuit being normally open and having a signal means operated thereby when closed, a circular timing dial marked to indicate units of time within a predetermined period of time, a rotatable disc formed with a plurality of holes in the upper surface thereof adjacent to the outer edge and in close spaced relation with said time units on the dial, an electrically operated motor connected in said circuit and to said disc providing movement thereof at a constant rate relative to the timing dial, a removable circuit controlling pin adapted to be inserted in the nearest one of said holes opposite a preselected time unit marked on the timing dial indicating a period of time which is to elapse before the signal circuit is closed, a normally open switch in said signal circuit provided with means arranged in a predetermined position on said timing dial to close said switch when said pin moves into contact therewith after travelling for the selected period of time, and marking means movably positioned to indicate the starting point of said pin in its travel relative to the timing dial.

2. A timer adapted to signal the passing of predetermined and varying periods of time comprising an electrical signal circuit adapted to be energized from a commercial power source, said signal circuit being normally open and having a signal means operated thereby when closed, a circular timing dial marked to indicate units of time within a predetermined period of time, a rotatable disc having a plurality of holes in the upper surface thereof adjacent to the outer edge and in close spaced relation with said time units on the dial, a uniform speed motor in said circuit and driving said rotatable disc; a plurality of removable circuit controlling pins adapted to be inserted in the nearest of said holes opposite preselected time units marked on the timing dial indicating varying periods of time which are to elapse before the signal circuit is closed; a nor-

mally open manually operated switch in said signal circuit provided with means arranged in a predetermined position on said timing dial to close said switch when the first of said pins move into contact therewith after travelling for its selected period of time, and a movable marker adapted to be positioned on the timing dial opposite the starting position of each of said pins to indicate the period of time travelled by each pin from its starting point relative to the circuit closing means.

3. A self calculating timer contained within a moisture sealed casing and adapted to signal the passing of predetermined and varying periods of time comprising in combination, an electrical signal circuit adapted to be energized from a commercial power source, said signal circuit being normally open and having a signal means operated thereby when closed, a circular timing dial marked to indicate units of time within a predetermined period of time, a rotatable disc formed with a plurality of holes in the upper surface thereof adjacent to the outer edge and in close spaced relation with said time units on the dial, an electrically operated motor connected in said circuit and to said disc providing movement thereof at a constant rate relative to the timing dial, a removable circuit controlling pin adapted to be inserted in the nearest one of said holes opposite a preselected time unit marked on the timing dial indicating a period of time which is to elapse before the signal circuit is closed, a normally open switch in said signal circuit provided with means arranged in a predetermined position on said timing dial to close said switch when said pin moves into contact therewith after travelling for the selected period of time, and a marker movably positioned on the timing dial to indicate the starting point of said pin in its travel relative to the timing dial.

GEORGE W. CARMICHAEL.
